UNITED STATES PATENT OFFICE.

CORNELIUS GRAY, OF WALNUT PARK, CALIFORNIA.

VENDING MACHINE.

Application filed February 24, 1927. Serial No. 170,653.

This invention relates to coin controlled vending machines and more particularly to machines that are especially adapted to vend materials such as gasoline and lubricating oil associated with the automobile industry. Practically every owner of an automobile has suffered the inconvenience of running out of gasoline at a late hour when all gasoline filling stations and garages have closed. 10 In such a predicament the driver is obliged to awaken some garage owner to negotiate for the purchase of gasoline. The frequent occurrence of such episodes has led to the rise of this invention, and it is an object of this invention therefore, to provide a machine which may be left unattended, and which machine is provided with suitable coin control means whereby the driver of a vehicle may insert a coin and secure a can 15 of gasoline, lubricating oil or the like.

A further object of my invention is to provide a vending machine in which the merchandise to be distributed is visible to the purchaser, so that he will not inadvertently deposit a coin in the machine believing that he will receive merchandise when the contents of the machine has been exhausted.

Yet another object of my invention is to 20 provide a vending machine which is strong and durable, which is comparatively inexpensive to manufacture, which operates efficiently, which is not likely to get out of order and which is well adapted to perform the services required of it.

With the foregoing and other objects in view, which will be made manifest in the following detailed description and specifically pointed out in the appended claims, 25 reference is had to the accompanying drawings for an illustrative embodiment of the invention, wherein:

Figure 1 is a side elevation of my vending machine partly in section, having a portion 30 of the same broken away to disclose the interior operative mechanical parts.

Figure 2 is a horizontal sectional view taken along the line 2—2 of Figure 1.

Figure 3 is a horizontal sectional view 35 taken along the line 3—3 of Figure 1.

Figure 4 is a side elevation of a portion 40 of my coin controlling mechanism showing details of construction thereof.

Figure 5 is a view taken in the direction 45 of the arrow 5 in Figure 4, and

Figure 6 is a perspective view of one of

the compartments wherein the merchandise to be distributed is stored.

Referring to the accompanying drawings wherein similar reference characters designate similar parts throughout, the reference numeral 1 designates a standard or platform upon which my improved vending machine is mounted. This platform is preferably shell-like in construction and is provided with a plurality of apertures 2 extending therethrough at points adjacent its periphery so that the machine may be suitably clamped to a foundation by means of suitable bolts or the like (not shown). 60 The center of this platform extends upwardly to form a hollow, supporting structure 3, and the upper end of this tubular supporting structure has formed thereon a table or the like 4, having a marginal depending apron 5. The tubular supporting structure is provided at a point intermediate its length with an internal, annular flange 6, upon which flange there rests a partition. The space above said partition provides a coin collecting tray which will be described hereafter. The table 4 has a central aperture therethrough; and mounted in this aperture is a short cylindrical sleeve member 9 having brackets 7 formed thereon. Apertures extend through these brackets 7 and these apertures are adapted to receive suitable bolts 8 which extend through apertures in the table 4, thereby enabling the sleeve 9 to be firmly clamped to the table 4 so that 70 its longitudinal bore extends vertically through the table on either side. Mounted within the sleeve member is a cylindrical tube 10, which cylindrical tube serves as a vertical supporting axis upon which elements of my coin control mechanism may be mounted. The tube 10 has an aperture 11 adjacent its lower end, registering with a similar aperture 12 in the sleeve 9, and a bolt 13 extends through these apertures and holds the supporting axis rigidly within the sleeve 9. The tube 10 extends upwardly 80 from the sleeve 9 to a point adjacent the top of the vending machine, and my actual dispensing container is supported upon this supporting tube which extends centrally through the same. The dispensing container is best shown in Figure 3 of the drawings, and consists of a plurality of compartments 90 95, which compartments are sector-shaped, being bounded by side walls 16, front walls 15, and doors 17 and rear walls 18. The front

100

105

110

and rear walls are arcuate in shape, and when in position these walls as an assembled whole, present the appearance of concentric cylinders shown in Figure 3. The side walls 5 or ribs 16 are provided at their outer ends with vertical grooves 19 on either side, and the front walls or doors 17 are vertically slidable in these notches. The ribs 16 and the rear walls 18 are adapted to rest on the table 4 as clearly shown in Figure 1. The space within the center of the rear walls is provided with a funnel-like structure having a conical body portion 21, and a depending spout 22 extending through an aperture in the table 4 to the coin receiving compartment 23 which has a bottom 24 resting on the flange 6, this bottom being the partition to which reference was previously made, and a door 25, which door may be controlled by a suitable locking mechanism such as a key-controlled latch or a combination-controlled latch. In each of the compartments 15 there is adapted to be stored a sector-shaped container which may be constructed of tin or the like, and which container conforms in configuration to the compartment 15. In each of these containers there may be stored gasoline, oil or the like.

Reference to Figure 1 of the drawings will reveal that mounted on the upper end of the radial ribs 16 is an inverted shell 26, which shell is provided with an annular downwardly extending flange 27. This downwardly extending flange has a plurality of cut-out portions 28 corresponding in number to the radial ribs 16. These cut-out portions are adapted to receive the outer ends of the radial ribs so that the shell 26 may be supported securely against rotation. The center of the shell-like structure 26 has an upstanding, annular flange 29 which forms the boundary of an aperture extending through the shell 26. Supported on the upper end of this flange 29 is a suitable casing 30 having a depending apron 31 receivable upon the flange 29 by means of a suitable sliding lap joint 32 (Figure 1), and an aperture 34 at its top, which aperture is bounded by a bearing surface 35 bearing against the tubular member 10. The casing 30 is rotatable upon the tubular member and upon the shell 26, and a hollow arm 36 is formed on the casing 30 and in this arm there is disposed a coil spring through which spring extends a plunger 37 having a handle 38 thereon and a handle 39 is formed on the outer end of the arm 36. The coil spring normally holds the plunger in an extended position by virtue of the fact that it is under compression between a shoulder 40 on the plunger 37 and the apron 31. A collar 41 clearly shown in Figures 1, 4 and 5 is mounted on the tubular member 10 and is secured thereto firmly by means of a suitable set screw 42 (Figure 1). This collar is pro-

vided with a plurality of inwardly extending sockets 43 (Figure 5) into which the ends of the plunger 37 are adapted to be selectively inserted. Formed on the tubular member 10 at a point intermediate its length 70 is a suitable collar 44. (The description in this paragraph may be read clearly in Figures 4 and 5 of the drawings.) This collar 44 has a plurality of vertically extending sockets 45 in which are disposed coil springs 75 46 and ball bearings 47. A pair of upwardly extending arms 48 and 49 are mounted in a collar 50, which collar rests upon the collar 44 and surrounds the tube 10. This collar has a plurality of depressions 51 circumferentially formed on its bottom surface, and when the collar 50 rests upon the collar 44, these depressions in conjunction with the ball bearings 47 and the springs 46, form a restraining means and a centering 80 means whereby the plunger 37 may be aligned with one of the sockets 43. The arms 48 and 49 are outwardly bowed as at 52 to accommodate the collar 41, and the upper ends of the arms 48 and 49 are connected together as at 53, and the tubular member 10 extends through this connection. Arms 48 and 49 have formed intermediate their length, suitable brackets 54, which brackets are apertured as at 55; and a pin 95 56 extending therethrough serves as a fulcrum at a point intermediate the length of a lever 57. The upper end of this lever 57 is forked as at 58, and the lower end of the same is provided with a slot 59. Formed 100 on the plunger 37 there is a shoulder 60 which serves the purpose to be hereinafter described. The lower ends of the arms 48 and 49 have an outwardly extending portion 61 which has an upwardly extending 105 projection 62. A coil spring 63 is attached to this projection at one end and the other end is attached to a swinging bifurcated bracket 64. The projection 62 is apertured and is adapted to receive a plunger 65, which 110 plunger is pivoted to the lower end of the lever 57, in the slot 59. The upper wall of the casing 30 is provided with a slot 66; and a split supporting bracket 67 is attached to the casing above the slot. A coin chute 115 designated as an entirety at 68 extends through the bracket and through the slot 66 to a point adjacent the plunger 65. The coin chute is preferably serpentined in form. Pivoted to the lower end of the coin chute as 120 at 69 by means of a suitable pin 70, is the bifurcated bracket 64 referred to before. The coil spring 63 serves to hold the bracket in preferred position abutting against the projection 62. The bifurcated bracket 64 125 has apertures 71 and 72 extending through the sides of the same, which apertures are slightly larger than the diameter of the plunger 65 and are adapted to receive the plunger 65 therethrough. On the arms 48 130

and 49 at their lower ends are narrow, inwardly extending arms 73 and 74, which arms oppose each other and their inner opposing ends are arcuately curved to receive between them the circumference of a coin 75. The bracket 64 has formed on one side thereof, a small finger 76 which serves as a plunger.

The inner walls 18 of the storage compartments have thereon a small bracket 77, to which bracket there is pivotally mounted by means of a pin 78, a bell crank lever 79, the lower end of which extends downwardly and is adapted to make contact with the finger 76. The upper end of the bell crank lever 79 has pivotally attached thereto a slideable rod 80, on the end of which is mounted a latch member 81 (Figure 2). This latch member comprises a housing 82 slotted as at 83, and within the housing there is anchored by means of a suitable pin 84 (Figure 1) a coil spring. A latch 85 is slideable within the housing 81 and is at all times forced outwardly by the action of the coil spring. The outer walls or doors 17 of the storage compartments have on their upper ends inwardly extending flanges 86 adapted to rest upon the latch member 85. The doors 17 have mounted on their inner surface, leaf-springs 87 secured to the door by means of suitable screws or the like 88. The outer ends of the cylindrical table 4 have slots 89 therethrough through which the doors 17 are adapted to slide downwardly. Each of these slots is provided on its interior with a cut-out portion 90 providing a shoulder 91, which shoulder acts as a stop.

There is mounted upon the upper end of the tubular member 10, a suitable cup-shaped bracket 92, the walls of which are adapted to receive set-screws 93. A suitable hollow, transparent globe 94 having a bottom flange 95 of such a size as to be just receivable within the cup-shaped collar 92, and the set-screws 93 engage the outer portion of this flange 95 to hold the globe-shaped member 94 in place. An aperture 96 is provided in this collar and in this aperture may be mounted a suitable light globe 97 to illuminate the globe 94. The collar 92 has diametrical opposed apertures 98 therethrough, and the upper end of the tube 10 has registered diametrically opposed apertures 99 and a pin 100 extends through these apertures to hold the collar in position on the upper end of the tubular member 10.

The operation of my device is as follows. When a coin is inserted in the slot of the coin-receiving chute, the coin thus deposited travels down the serpentine chute and is received between the apertured sides 71 and 72 of the bifurcated bracket 64, where it is held in position between the arcuate surfaces on the inner opposed ends of the shoulders 73 and 74. The arm 36 is then ro-

tated until the plunger 37 is directly opposite one of the sockets 43. A perfect alignment will be insured since the ball bearings 47 restrain the rotation of the coin controlling assembly. The handle 38 is depressed and the plunger is received in one of the sockets 43. The shoulder 60 abuts against the bifurcated end of the lever 57, and acting on the pin 56 as a fulcrum, the lower end of the lever pushes the plunger 65 into the aperture 71 against the coin 75 in the bifurcated bracket. The bracket being pivoted at 70 swings outwardly against the pressure of the plunger 65, and the projection or finger 76 engages the bell crank lever 79; and acting on the pin 78 as a fulcrum, the upper end of said bell crank lever causes the slideable rod 80 to move inwardly and release the latch 85 from under the flange 86 of the door 17. The door 17 being slideable in the grooves 19, falls by virtue of its own weight. The leaf spring 87 bearing against the sides of the container within the compartment 15, serves to set up a resistance so that the door will not drop too rapidly. When the leaf spring 87 engages the shoulder 91, the dropping action of the door is still further restrained and the flange 86 comes to rest gently upon the shoulder 91. The container having the gasoline or lubricating oil therein, may then be removed from its compartment. When the purchaser has emptied a compartment, the door remains down as shown on the right hand side of Figure 1, so that a subsequent purchaser will not deposit a coin to open a compartment which has already been emptied. Upon releasing of the plunger 37, the lever 57 swings back to its normal position by virtue of the action of the coil spring 63, and the plunger 65 is retracted, releasing its engagement upon the coin 75; and the coin thus released falls into the cone of the funnel 21, through the spout 22 and into the coin compartment 23.

To insure the owner of the machine from illegal procuring of merchandise through the use of coins having a face value less than the value of the coin for which the coin-receiving apparatus has been designed, or through the use of washers or the like, my coin controlling apparatus has been especially designed. If no coin has been inserted in the coin-receiving slot or if a washer has been inserted, the plunger 65 will go completely through the apertures 71 and 72 and will not engage the swinging bifurcated bracket 64, so that the latch 85 will not be operated. I contemplate designing my vending machine so that the coin controlling apparatus will be adapted to operate successfully when a silver half dollar or dollar is inserted in the same. I may provide compartments with gasoline or oil containers therein of such a size as to store

one or two or more gallons of gasoline. If a coin smaller than the coin legally adopted is inserted, same will pass between the arms 73 and 74 directly into the coin-receiving chamber. The device is thus practically insured against fraud. The only manner in which an operator might illegally gain possession of the contents of one of the compartments, would be to drop in a coin and so time the falling of the same that the plunger 37 might be depressed at the instant the coin passes through the bifurcated bracket 64, but in view of the fact that the operative connections of the coin-controlling mechanism are concealed, the possibility of a person doing this would be extremely small.

The illuminating effect at the upper extremity of my vending apparatus may be of any conventional type, and if desired, suitable advertising material may be painted or otherwise formed on the transparent or translucent globe 94. A suitable plate 101 may be fastened at any particular point on the machine, said plate having printed thereon directions for operating the machine and the legal price for which the merchandise contained within a compartment is offered. It is not necessary that the same liquid be stored in each compartment. One compartment may store gasoline and another may store lubricating oil. One compartment may store a particular brand of gasoline and another compartment may store a different brand of gasoline. Similarly, the grade of the oil may be different in each compartment, and if such is contemplated, the outer side of the door panel may have printed thereon the contents of each compartment so that the purchaser will not open a compartment and secure merchandise he does not desire.

I do not desire to limit myself to the use of my construction for vending motor oils, gasoline or the like. I contemplate making various changes in the construction of my device. The device is especially handy for use in automatic restaurants where the doors 17 may be formed of glass, and various cold dishes may be stored within the compartments. I further contemplate changing the size and mechanical details of my construction so that the same may readily adapt itself to the vending of any sort of articles. Handkerchiefs, combs, candy and other articles may be vended by my improved machine. I desire to limit myself only in so far as the scope of the appended claims may determine.

It will be understood that various changes in the detail of construction may be made without departing from the spirit or scope of the invention as defined by the appended claims.

I claim:

1. A vending machine comprising in combination a base, a storage chamber mounted on said base, said storage chamber being divided into compartments, a door for each of said compartments, a latch adapted to hold each of said doors in closed position and manually operated means for selectively releasing said latches to allow said doors to open and reveal the contents of said compartments. 70 75

2. A vending machine comprising in combination a substantially cylindrical storage chamber, said chamber being divided into compartments by radial side walls, said side walls having grooves adjacent their outer ends, doors slidably mounted in said grooves, said doors being held in position by latches and means for selectively releasing said latches that access may be had to said compartments. 80 85

3. A vending machine comprising a substantially cylindrical storage chamber, said chamber being divided into compartments by radial side walls, grooves adjacent the outer end of said side walls, doors slidably mounted in said grooves, said doors having an inwardly extending flange, latches receivable beneath said flanges to hold the doors in closed position, springs on the inner sides of said doors adapted to bear against articles placed in said compartments and means for selectively releasing said latches to allow said doors to slide against the frictional resistance of said spring that access may be had to said compartments. 90 95 100

4. A vending machine comprising a storage chamber, said chamber being divided into storage compartments having side walls, grooves in said side walls, doors slidably mounted in said grooves, means for retaining said doors in closed position with respect to said compartments, means for releasing said doors that access may be had to said compartments, and means for frictionally retarding the sliding movement of said doors. 105 110

5. A vending machine comprising a storage chamber, said chamber being divided into storage compartments having side walls, grooves in said side walls, doors slidably mounted in said grooves, means for retaining said doors in closed position with respect to said compartments, means for releasing said doors that access may be had to said compartments, and means for frictionally retarding the sliding movement of said doors, said means comprising a leaf spring on said doors adapted to bear against articles of merchandise in said compartments. 115 120 125

6. A vending machine comprising a storage chamber divided into compartments having side walls, said side walls having grooves therein and doors slidably mounted in said grooves, latch means for holding said doors in closed relation with respect to said 130

compartments, means for selectively releasing said latch means to permit said doors to slide in said grooves that access may be had to said compartments and means for frictionally retarding the movement of said doors, said last mentioned means constituting a stop to hold said doors in said grooves in open position.

7. A vending machine comprising in combination a substantially cylindrical container, said container being divided into compartments by means of radial side walls, grooves in the outer ends of said side walls, arcuate doors slidably in said grooves, said doors having inwardly extending flanges, latches underlying said flanges and means for selectively releasing said latches to allow said doors to slide in said grooves, a leaf spring on the inner side of said doors adapted to bear against articles of merchandise in said compartments, to frictionally resist the sliding movement of said doors.

8. A vending machine comprising in combination a container having top and bottom walls, said container being divided into compartments having side walls, grooves in said side walls and doors slidable in said grooves, latch means for retaining said doors in closed position, and means for selectively

releasing said latches to allow said doors to slide in said grooves, shoulders on said bottom wall and a stop on said door adapted to abut against said shoulder when said latch is released, to retain said door in open position.

9. A vending machine comprising in combination a support, a substantially cylindrical container mounted on said support, said container having top and bottom walls and being divided into compartments by radial side walls, grooves in the outer end of said side walls, arcuate doors slidably mounted in said grooves, flanges on said doors and latches adapted to extend beneath said flanges to hold the doors in closed position, means for selectively releasing said latches to allow said doors to slide in said grooves, shoulders on said bottom walls, a leaf spring on said door adapted to bear against articles in said compartments to frictionally resist the sliding movement of said doors, said flange being adapted to abut against said shoulders to retain said door in open position with respect to said compartment.

In testimony whereof I have signed my name to this specification.

CORNELIUS GRAY.
